CLAIM

The ornamental design for a game controller charger base, as shown and described.

DESCRIPTION

FIG. 1 is a front, right and top perspective view of a game controller charger base showing my new design;

FIG. 2 is a rear, left and bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines shown in the figures are for the purpose of illustrating portions of the game controller charger base that forms no part of the claimed design.
